F. E. Sickels,

Steam-Engine Valve-Gear.

Patent No. 8,760.

Patented Feb. 24, 1858.

UNITED STATES PATENT OFFICE.

FREDERICK E. SICKELS, OF NEW YORK, N. Y.

CUT-OFF.

Specification of Letters Patent No. 8,760, dated February 24, 1852.

To all whom it may concern:

Be it known that I, FREDERICK E. SICKELS, of the city, county, and State of New York, have invented a new and Improved Mode 5 of Tripping Cut-Off Valves; and I do hereby declare that the following is a full and exact description thereof, reference being had to the accompanying drawings and to letters of reference marked thereon.

10 In cut-offs as heretofore constructed, in operating the catch by the closing movement alone, the valve could not be tripped until sufficient motion had taken place to operate the whole extent of the catch, thus 15 occasioning an unavoidable delay in tripping the valve.

The nature of my invention therefore consists, in operating the catch or hold, and liberating the valves of trip cut-offs, on the 20 movement to close, or return of the valve motion by means of an adjustable cam or lever, after it has been partially operated upon, on the opening movement of the valve motion, so as to leave as little movement of the 25 catch to effect the liberation of the valve as may be desired to be accomplished by the return movement; thereby being enabled to liberate the valve, and cut off the steam, as near the first of the return movement as 30 may be desired.

Figure 1, side view. Fig. 2, front view.

A, toe on the rock shaft. B, foot on the lifting rod. C, lifter. D, valve stem. E, catch piece on lifter, having a projection 35 catching under the socket F, at G, H.

J and K are two arms, having wedges or inclined planes L, M, upon them as shown in Figs. 3 and 4; they being edge views and the same letter referring to the same parts 40 in each figure. N, lever upon which the arms J and K, connect with joints at O, and P—the lever itself vibrating upon a pin at Q, and being connected with an adjusting rod S, by a joint and pin at R. U an adjusting screw socket working on the adjusting rod S. E, Fig. 5, top view of catch piece or lever having a projection catching under the socket F, at G, H. V wedge piece on K, having its inclined plane or wedge surface 45 running in the direction from 1 to 2. The other wedge pieces on the arms J and K having their wedge or inclined surfaces running as shown in edge views of the arms 50 Figs. 3 and 4, in the direction from 4 to 5 and from 6 to 7. One wedge having its

larger part downward as shown in Fig. 4, and the other, the larger part upward as shown in Fig. 3. W, Figs. 3 and 4 section of lifter holding the lower end of the arms J and K, from being moved out of their proper position when the wedges L and M act upon the catch piece. x x Figs. 3 and 4 section of catch piece at the part where it is acted upon by the wedges L and M, its extreme end at that part being beveled in 60 the direction from 8 to 9 Fig. 1.

The operation is as follows: The wedges or inclined planes L, M, V, being in the position shown in the drawings (Figs. 1 and 2), and the catch piece E, moving upward, 70 in the opening movement from the dotted line Y to the dotted line Z, as represented in the drawing in Figs. 1, 2, 3, and 4. Then as the catch piece moves upward, its inclined end at 8, 9, strikes the face of the wedge or inclined plane V, at 1, 2, and moves it in the direction of from 10, to 11, the arm K, turning on a joint at P; the wedge L, moving out the catch piece, until it has reached the extent of its upward movement, and is 80 about to return, the projection on the catch piece being then under the socket, as shown in Fig. 5, and the end of the catch piece being 85 in the position shown by red lines 12, 13, Figs. 3 and 4. The wedge M, now moves back under the end of the catch piece, the arm K, turning on the pin at P, and being actuated by a ball or weight &, on a horizontal extension of the arm K. Now by the first of return movement, the catch piece 90 passes over the larger part of the wedge M, and is thereby entirely moved out from under the socket, and the valve attached to the valve stem is permitted to close.

By turning the adjusting screw socket U, 95 so as to lower the wedge L, and raise the wedge M, the catch piece would be farther moved out from under the socket by the opening motion, and leave less to be accomplished by the return motion, thereby cutting off the steam nearer the first of the return movement, and by turning the adjustable socket, so as to raise the wedge L, and lower the wedge M, the upper movement 100 would operate the catch piece less, and the downward movement more, thereby cutting the steam off farther from the first of the return movement.

Fig. 6, represents in perspective, a portion of the two arms J, K, with their wedges 110

or inclined planes L, M, V, and the catch piece E, detached from the other parts of the apparatus.

Having thus fully described my invention what I claim therein as new and desire to secure by Letters Patent, is—

Operating the catch or hold, and liberating the valves of cut-offs, on the movement to close, or return motion of the valve after it has been partially operated upon in opening, substantially in the manner as herein

described so as to leave as little of the catch to be operated, to effect the liberation of the valve, as may be desired to be accomplished on the return movement, thus being 15 enabled to liberate the valve and cut off the steam, as near the first of the return movement as may be desired.

FREDERICK E. SICKELS.
